(57) **CLAIM**

The ornamental design for a lamp as shown and described.

DESCRIPTION

1. Lamp

1.1 : Perspective

1.2 : Back

1.3 : Right

1.4 : Bottom

1.5 : Enlarged

1.6 : Enlarged

1.7 : Cross sectional

1.8 : Front

1.9 : Top

1.10 : Left

Figures 1.5 and 1.6 are enlarged views of the end of the bar of the lamp; Figure 1.7 is a cross-sectional view of the bar of the lamp; the broken lines shown in the figures illustrate portions of the lamp which form no part of the claimed design; the break lines and the curly brackets shown in figures 1.1 to 1.6, 1.8, 1.9, and 1.10 illustrate symbolic breaks which form no part of the claimed design and indicate an indeterminate length of the lamp between said break lines; the appearance of any portion of the lamp between said break lines form no part of the claimed design; the dash-dot lines represent bounds of the enlarged detail view and form no part of the claimed design.

1 Claim, 10 Drawing Sheets
